DESIGN FOR A COMBINATION TANK AND PACKAGE DELIVERY BODY FOR VE- HICLES

Andrew A. Kramer, Joseph M. Kramer, and Ferdinand C. Buchanan, Kansas City, Mo.; said Joseph M. Kramer and said Buchanan assignors to said Andrew A. Kramer

Application September 20, 1935, Serial No. 58,629

Term of patent 14 years

To all whom it may concern:

Be it known that we, Andrew A. Kramer, Joseph M. Kramer, and Ferdinand C. Buchanan, citizens of the United States, residing at Kansas City, in the county of Jackson and State of Missouri, have invented a new, original, and ornamental Design for a Combination Tank and Package Delivery Body for Vehicles, of which the following is a specification, reference being had to the accompanying drawing, forming a part thereof.

The figure is a perspective view of our new design.

The side of the body opposite that shown in

the drawing is of substantially the same design as that shown. The forward end of the body is substantially plane faced. The upper portion of the body is an open topped package carrying compartment and the lower portion is a tank compartment underlying the open topped package carrying compartment.

We claim:

The ornamental design for a combination tank and package delivery body for vehicles substantially as shown and described.
